Primary Examiner — Mitchell Siegel

CLAIM

The ornamental design for a golf club hosel sleeve, as shown and described.

DESCRIPTION

FIG. 1 is a top perspective view of a golf club hosel sleeve; FIG. 2 is a bottom perspective view of the golf club hosel sleeve of FIG. 1;

FIG. 3 is a front elevational view of the golf club hosel sleeve of FIG. 1;

FIG. 4 is a rear elevational view of the golf club hosel sleeve of FIG. 1;

FIG. 5 is a top view of the golf club hosel sleeve of FIG. 1; FIG. 6 is a bottom view of the golf club hosel sleeve of FIG. 1;

FIG. 7 is a left side view of the golf club hosel sleeve of FIG. 1; and,

FIG. 8 is a right side view of the golf club hosel sleeve of FIG. 1.
